GRAIN BIN INDICATOR

Abraham M. Unruh, Sterling, Colo.

Application March 9, 1948, Serial No. 13,929

1 Claim. (Cl. 116—118)

1

This invention relates to a grain bin indicating signal, that is, to an indicating device for giving a visible signal or indication when a grain bin or elevator has been filled or emptied to a certain point, and has for its principal object the provision of a simple, positive, and inexpensive device which can be quickly and easily installed in the wall of a bin, tank, elevator, or the like, and which will operate by the grain in the bin to give a visible signal without the use of electrical connections of any nature.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Figure 1 is an outside face view of the improved indicating signal in the filled position;

Fig. 2 is a vertical section through the indicating signal of Fig. 1, taken on the line 2—2, Fig. 1, and

Fig. 3 is a similar section, illustrating the indicator in the empty position.

In the drawing, the wall of a typical bin or elevator is indicated at 10. The improved indicator is installed by forming an opening 11 in the wall 10 and covering the external orifice of this opening by means of a sheet metal pocket 12. The pocket 12 extends through the bin wall 10 and is secured to the wall by means of two side flanges 13 and suitable attachment devices 14. The attachment devices, of course, depend upon the nature of the wall 10. They may be wood screws, toggle bolts, expansion shells, or any other suitable attachment devices.

The pocket 12 has two triangular side walls and a front wall which extends upwardly and outwardly at a rather steep angle to an inclined top plate 15. The top plate joins the front plate at an angle of substantially 90° and is provided with a rectangular opening 16. A hinge wire or rod 17 extends across the inside of the pocket 12 above the upper edge of the opening 16 and swingingly supports a rectangular valve plate 18.

The plate 18 is preferably formed from relatively light sheet metal and is attached to the rod 17 by rolling its upper edge around the rod, as shown in Fig. 3. The plate 18 conforms in shape to the opening 16 and is of larger dimension than the opening so that it cannot swing through the latter.

A signal tab 19 is secured to the plate 18 adjacent its hinged edge and extends outwardly therefrom at a comparatively wide angle, as

shown in Fig. 3. The signal tab is of a size which will pass through the opening 16 and its under face is preferably painted or enameled some bright, contrasting color such as red or yellow, so that it will be easily visible.

When the bin is empty, the tab will swing below the pocket 12 so that it will not be visible as shown in Fig. 3. When the bin is filled, as shown in Fig. 2, the weight of the grain rolling 10 against the plate 18 will force it outwardly and upwardly to close the opening 16. When in this position, the tab 19 projects so as to be easily visible to an operator standing below the pocket 20.

15 It is desired to call attention to the simplicity of this device, there being only one positively operated and cheaply constructed moving part.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A filling indicator for grain bins comprising: A pocket secured over an opening in the wall of the bin and extending outwardly from the exterior thereof; two triangular side plates, there 25 being one side plate closing each side of said pocket; an outwardly and upwardly inclined front plate, and an inwardly and upwardly inclined top plate, the front and top plates forming an angle of substantially 90° with each other, there 30 being an opening in said top plate; a swinging flap valve plate pivotally suspended from a point above said opening and on the interior of said pocket so that it may swing against the inside of said top plate to close said opening; and a signal 35 tab rigidly secured to the outer face of said valve and extending outwardly therefrom at an angle, said valve being of a size greater than said opening, said tab being of a size less than said opening so that when said valve is open said tab will 40 swing into the interior of said pocket so as to be invisible and when said valve is swung against the inside face of said top plate by the pressure of grain within said bin, said tab will project through said opening and upwardly therefrom to 45 give a visible signal indication.
